UNITED STATES PATENT OFFICE.

JOHN J. BERRIGAN, OF CHICAGO, ILLINOIS, ASSIGNOR OF ONE-THIRD TO JOHN B. BERRIGAN AND ONE-THIRD TO KATHERYNE P. MALON, BOTH OF CHICAGO, ILLINOIS.

HYDRAULIC PRESS.

Application filed November 14, 1923. Serial No. 674,608.

To all whom it may concern:

Be it known that I, JOHN J. BERRIGAN, a citizen of the United States, residing at Chicago, in the county of Cook and State of Illinois, have invented a certain new and useful Improvement in Hydraulic Presses, of which the following is a specification.

This invention relates to a hydraulic press and particularly to a double hydraulic press. It has for one object to provide a double hydraulic press utilizing a single pressure creating means and constructed so that this means may be used to press one side while the other is being filled, and may then be used to compress the second side while the first is being emptied.

Heretofore hydraulic presses of large capacity have been all single, that is to say, there has been a single pressure creating means for each press. When the press is filled, the compression action is commenced. This is of comparatively short duration. As soon as sufficient compression has been attained, the press is opened and emptied. The emptying operation and the subsequent filling operation require considerably longer time than does the pressing, and thus during the greater part of the time the compression device is idle. In my invention I have provided means whereby the compression device is connected to two sections of a double press. While one section is being filled, the other section is in the pressing operation, and as soon as that section is completely compressed and while it is being emptied, the other side is subject to compression. Thus the compression device is in operation most of the time, and the operation of the press is very much more economical both with regard to power and labor.

My invention is illustrated more or less diagrammatically in the accompanying drawing, wherein:

Figure 1 is a partial side elevation showing the press;

Figure 2 is a longitudinal vertical cross section on an enlarged scale showing the bag mounting arrangement;

Figure 3 is a vertical section showing an end of one of the bags;

Figure 4 is a vertical cross section taken on line 4-4 of Figure 1 on an enlarged scale.

Like parts are indicated by like characters throughout.

The press proper is mounted on a frame work. This frame work is made up of end pieces A A, only one of which is here shown and side channels A¹ A¹ which are connected to the end pieces. Mounted between the side channels A¹ A¹ is a hydraulic pressure cylinder B. This cylinder is provided with a pair of upper, laterally extending flanges B¹ B¹ and a corresponding lower pair of flanges B² B². The upper flanges extend laterally and lie upon the tops of the side channels A¹. The lower flanges B² engage the under face of the side channels. The pressure cylinder B is thus mounted so that it can slide along the channels with relation to the frame of the press. The flanges of the channels A¹ are perforated at suitable points as at A² A² and the flanges B¹ B² are also perforated as at B³ B⁴. Pins B⁵ may be inserted through the perforations above mentioned and the cylinder is thus held against lateral displacement. When the pins are removed the cylinder may be moved so as to bring the perforations in the flanges in register with the perforations in the channel and the pin may then be replaced and the cylinder held against further movement. By this means the cylinder may be moved to different positions along the frame.

A piston C is mounted within the cylinder. It is provided with a rod C¹ which extends laterally from it and out through the head of the pressure cylinder.

The cylinder is normally held substantially in the middle of the press. Mounted on one side, on the right as it appears in Figure 1, is a platen D, having laterally extending flanges D¹, the upper of which flanges rest upon the channels A¹ and the lower of which contact the under face of the channel and serve to guide the platen. This platen is fixed to the rod C¹ and operates in connection with a second platen D². Between the two platens are mounted a plurality of partitions E. They may be sup-

ported within the press in any suitable manner, but as here shown are notched on their sides so as to extend over and rest upon the channels A^1 . Extending between the platens D D^2 and engaging each of the partitions E are a plurality of chains E^1 . These chains serve to space the partitions when the press is open. Other spacing means might be provided but I prefer to 10 use the spacing chains shown.

Fastened to the flanges D^1 and extending downwardly from them and enclosing the channels A^1 are a pair of plates F . The flanges D^1 are perforated and a pin may 15 be inserted through these perforations, and through the perforations in the flanges of the channels A^1 to hold the platen against displacement. The platen, however, is not held against displacement except when the 20 pressure cylinder B is free to move.

Either the cylinder or the piston is moved laterally backwards and forwards during the pressing operation. When one is to be moved, the other is fixed. Each is mounted 25 so that it can be fixed, but only one, of course, is held against movement at one time. As shown in Figure 1 the cylinder is fixed and the piston is free to move.

Secured to the platen D and mounted to 30 move with it are one or more rods G . These rods extend through perforations in the platen D^2 and are themselves perforated as at G^1 .

The channels A^1 are perforated as at A^1 35 and through these perforations a pin A^4 may be inserted. Against this pin the platen D^2 will rest and the pressing effect is exerted upon the pin. By this means the platen D^2 may be held against the pressing movement in a number of different positions.

Lying between the partitions E E are a 40 plurality of bags H H . These bags as shown are perforated in their sides and these perforations are in register with perforations in the partitions E . A short length of pipe H^1 H^1 passes through the perforations in the bags and the perforations in the partitions and is held in position by nuts H^2 which also grip the fabric of the cloth and hold it in position. Each of the bags is provided in its top with a tape or fabric strip H^3 . This strip passes over the upper end of one of the partitions 45 E and is held in position there by means of a spring clip H^4 . This construction is designed to prevent the accidental displacement of the bags when the press is empty or being emptied or being filled.

The bags themselves are in fact open ended tubes. Extending across each end of each tube on each side is a pocket I . Within this pocket a thin plate of metal I^1 is inserted. When the bag is to be filled the 50 end is closed bringing the two plates to-

gether and the end of the tube is then folded over twice. The pressure of the material within the bag as the bags are filled and as pressing commences tends to force the end of the bag against the partition, and thus as the pressure increases the seals at the ends of the bags become tighter. 70

The end of the press which is shown to the left of Figure 1 is practically identical 75 with that shown to the right. In this case, however, the first platen J is secured directly to the pressure cylinder B and moves with it. There are provided a pair of plates K which are secured to the flanges B^1 B^2 80 of the cylinder B in the same manner as the plates F are secured to the flanges D^1 of the platen D . Mounted also so as to move with the cylinder B and the platen J are one or more rods L . These rods correspond exactly to the rods G and operate in the same manner. M M are flexible connections by means of which pressure, hydraulic or otherwise, is forced first to one side of the cylinder and then to the other 85 so as to move either the cylinder back and forth or the piston. 90

N is a flexible connection by means of which material to be pressed is pumped into the bags, as shown on the right in Figure 1. Through this connection the bags are filled first one and then the other until the entire series is filled. The connection is then closed and the pressing may commence. A similar connection is used on the other side of the press for filling that side. 95

Although I have shown an operative device, still it will be obvious that many changes in size, shape and arrangement of parts might be made without departing materially from the spirit of my invention; and I wish therefore that my showing be taken as in a sense diagrammatic. 100

Where in the claims and specification the words "pressing assembly" are used, it 110 means the essential parts of the pressing apparatus, for example, a pair of platens and the material holding parts between them. As applied to Figure 1 a pressing assembly would constitute the platens D D^2 and the bags and holding means between them. 115

The use and operation of my invention are as follows:

When it is desired to use the press, both sides may be opened. They may then be 120 filled simultaneously. Then assuming that the side to the right in Figure 1 is to be pressed first, the following operation will be carried out. The cylinder will be fixed by means of the insertion of the pin B^5 . When the press is full, the platen D^2 will occupy the position shown in dotted lines in Figure 1 and indicated by X . Pressure is then applied so as to move the piston outward, thus moving the platen D toward the 130

- right and compressing the entire contents of the press against the platen D² which rests against the end of the press. When the piston is moved outward its full excursion. 5 pressure is stopped and a small pin G² is inserted in one of the perforations G¹ of the rods G. Pressure is then put upon the opposite side of the piston so as to withdraw it into the cylinder, moving with it the entire press, since the platen D is fastened to the platen D² by means of the rods G. The entire right side of the press is then moved to the position shown in full lines in Figure 1. Then a pin A⁴ is placed in the hole 10 A³. Pressure is then again reversed, the platen D moving toward the platen D², pressing the contents against this platen, which in this case is held by the pin A⁴. This operation may be repeated several 15 times, each time compressing the press through a distance equal to the effective length of the pressure cylinder and then moving the press inward and recompressing through the same distance. 20 When this operation is complete and the contents have been sufficiently compressed, the press is opened and may be emptied. As soon as it is opened the platen D is held against movement by the insertion of a pin, 25 and the pin B⁵ is removed so that the pressure within the cylinder will cause the cylinder to move backward and forwards and by this means the left side of the press is compressed in the same step by step movement. 30 During this operation, however, the right side of the press is emptied and refilled, and thus the crew of the press is able to fill one side while the other is being compressed, 35 and as soon as the pressing is finished they can empty that side and proceed with the pressing of the other. 40 I claim:
1. In a press, a plurality of pressing assemblies, and a single pressure applying means adapted to operate alternately on each of said pressing assemblies, the other remaining stationary during that operation. 45
  2. In a two part press a two part pressure applying means, each part of said pressure applying means being fastened to one part of said press and means whereby either half of the press may be compressed while the other remains stationary. 50
  3. In a press, a plurality of pairs of platens, and a single pressure applying means adapted to act alternately on each 55
- pair of platens, and means for moving each of said pairs of platens together through a distance greater than the effective length of 60 said pressure applying means. 65
4. In a press, a plurality of pressing assemblies, and a single pressure applying means adapted to operate alternately on each of said pressing assemblies, the other remaining stationary during that operation, and means for compressing each of said pressing assemblies through a distance greater than the effective length of the said pressure applying means. 70
  5. In a press, a plurality of pairs of platens each of said platens being movable and a pressure cylinder, and means for applying said pressure cylinder to compress first one of said platens and then the other. 75
  6. In a hydraulic press, a plurality of pairs of platens and a single hydraulic cylinder and means for applying said cylinder to compress alternately each of said pairs of platens, and means for compressing said 80 pairs of platens throughout a distance greater than the effective length of said hydraulic cylinder. 85
  7. In a press a two part pressure applying means, means for securing each of said parts against movement, a pair of platens on each side of said pressure applying means, one of said platens being secured to one of said parts, and the other of said platens being secured to another of said parts, each of said 90 parts adapted to move, to move the platen to which it is attached when the other of said parts is held against movement. 95
  8. In a hydraulic press, a main supporting frame, a hydraulic cylinder mounted 100 therein, a piston and piston rod adapted to move within said cylinder, means for securing said piston to said frame to prevent its movement and means for securing said cylinder to the frame to prevent its movement, a pair of platens on each side of said cylinder, one of said platens being secured to the cylinder, and another of said platens being secured to the piston, said piston adapted 105 to be reciprocated and to move the platen to which it is attached when the cylinder is held against movement, and said cylinder adapted to be reciprocated and to move the platen to which it is attached when said piston is held against movement. 110
- Signed at Chicago county of Cook and State of Illinois, this 12th day of November 1923.

JOHN J. BERRIGAN.
